Des. 237,672
Patented Nov. 18, 1975

237,672

SHELF HANGING DISPLAY CONTAINER OR SIMILAR ARTICLE

Ronald H. Taub, Highland Park, Ill., assignor to Taub Family Trust

Filed May 28, 1974, Ser. No. 473,410

Term of patent 14 years

Int. Cl. D20—02

U.S. Cl. D6—199

FIG. 1 is a perspective view of a shelf hanging display container or similar article showing my new design, the edge of a shelf being shown in broken lines for illustrative purposes only;

FIG. 2 is an end elevational view thereof;

FIG. 3 is a top plan view thereof;

FIG. 4 is a rear elevational view thereof;

FIG. 5 is a bottom plan view thereof; and

FIG. 6 is an inverted perspective view thereof, with the container in a closed position.

I claim:

The ornamental design for a shelf hanging display container or similar article, as shown.
